LIGHTING DEVICE FOR GAS BURNERS

Daniel J. Schoenberger, Cleveland, Ohio, assignor
to The W. J. Schoenberger Company, Cleveland,
Ohio, a corporation of Ohio

Application February 23, 1934, Serial No. 712,676.

4 Claims. (Cl. 251—131)

The present invention relates to a lighting device for use in connection with the burners of gas stoves. The general object of the invention is to provide a lighting device comprising a valve 5 of simple and economical construction which can be readily applied to stoves having variously arranged burners and main gas supply manifolds therefor.

The invention is illustrated in the accompanying drawing, in which:

Figure 1 is an enlarged cross sectional view of the lighter showing one arrangement of the gas manifold;

Figure 2 is an enlarged cross sectional view 15 of the lighter showing another arrangement of a gas manifold.

Figures 3 through 8 inclusive show the lighter disassembled, thus Figure 3 is a sectional view through the hood supporting nut; Figure 4 is a 20 side view of the spring for holding the air controlling sleeve; Figure 5 is a sectional view of the air control sleeve; Figure 6 is a longitudinal sectional view through the lighter body, showing the working relationship of the valve and valve adjusting member; Figure 7 is a sectional view through the adapter nipple and Figure 8 is a side view of the plug employed for closing either the side or bottom adapter opening in the lighter body.

Figure 9 is a transverse sectional view taken on 30 the line 9—9 Figure 6.

My improved lighting device or valve comprises a Bunsen type of pilot burner 12, the body portion 13 of which is formed with a threaded opening 14 at its lower end, and a second threaded opening 15 in one side thereof, each of which openings communicates with the cylindrical gas chamber 16. An externally threaded nipple 17 when screwed at one end into either of the openings 14 or 15 is adapted to be connected at its other end either to the top or side of a gas manifold. Where a centrally disposed manifold 4, is employed such as disclosed in Figure 1, the manifold will be preferably provided with a threaded top opening 18 into which the outer end of the nipple is screwed, for supporting the body of the pilot burner or valve in upright position symmetrically with respect to the burners.

The threading and size of the nipple at both ends of the latter preferably corresponds in size 50 and threading with that of openings 14 and 15 so that either end of the nipple will fit either of these openings. One of the openings 14 and 15 must of course be plugged and for this purpose I provide a screw cap or plug 20 adapted to be screwed into that opening which is not em-

ployed to receive the nipple. It will thus be seen that the lighter body is adapted for convenient connection either to the side or top of a manifold. A wrench engaging portion 19 is formed intermediate the ends of the nipple for an 5 obvious purpose.

My invention as heretofore stated is designed particularly for gas ranges and as shown in Figure 1 of the drawing the extension 21 of the body portion 13 is provided with a hood 23 having 10 openings adapted to receive tubes leading to the burners for conveying the flame thereto, all of which is well understood by those skilled in the art.

It will also be noted that in Figure 2, a modified form of manifold arrangement, the lighter body is supported by a pipe 25, the inner end of which screws into side opening 15. The outer end of the pipe 25, connects with the top of manifold 4', by means of an elbow coupling 26, 20 and thus provides for a free flow of gas from the main manifold to the chamber 16 of lighter body 13. Of course it will be understood that the elbow may be dispensed with and pipe 25 connected directly with an opening (not shown) formed in 25 the side of manifold 4'.

The flow of gas through the cylindrical chamber 16 in body 13 of the pilot burner 12, and thence through a small opening 27 into a mixing chamber 28 in threaded extension 21, is 30 regulated by a needle valve 29 having a rectangular body 30 terminating at one end in a needle point 31, and at the other end thereof having a smooth face 32, preferably beveled at an angle of approximately 45°. Rectangular body 30 is 35 guided in cylindrical chamber 16 for free sliding movement therein. An adjusting screw 33 threadedly mounted in a transverse opening 34 leading through the wall of body portion 13 to chamber 16 is formed with a cone shaped head 40 35 beveled at a 45° angle to provide snug contact with the beveled face 32. A coil spring 36 surrounding needle point 31, and bearing at opposite ends against the needle valve and the upper end of chamber 16, respectively, constantly 45 forces the beveled face 32 downwardly against the beveled head thus insuring that the valve will not stick or otherwise become accidentally closed. When adjusting screw 33 is screwed inwardly the needle valve 29 will be forced upwardly against the tension of spring 36, and the needle point 31 will partially close the opening 27, and when rotated in a reverse or anti-clockwise direction the screw 33 will move outwardly 50 and permit valve 29 to drop by gravity and under 55

the influence of the spring 36, thus permitting a greater volume of gas to pass through opening 27. A lock nut 37 and asbestos washer 38 prevent gas from leaking through the opening 34. 5 A shoulder or lug 40 at the upper end of the beveled face 32 of the needle valve 29, serves as a stop to limit the outward movement of adjusting screw 33 and accidental withdrawal of the head 35 through the opening 34. Any 10 suitable means such as a rotatable apertured collar 39 is employed to regulate the admission of air through openings 41 leading to chamber 28, and a nut 42 holds the hood and pilot burner securely together.

15 While it is essential that a pilot burner of the type herein disclosed, that is, one having an axially movable needle valve capable of fine adjustment, be employed in pilot burners, the use of such needle valves frequently presents many 20 difficulties. In this connection centrally disposed main gas manifolds have not come into general use due to the difficulties encountered in centering the pilot burners of the needle valve type with respect to the several main burners of the 25 stove, due to the fact that connection to the manifold must be made from the side, because the means for adjusting the needle valve is conventionally located at the lower end of the burner and consequently interferes with direct connection 30 with the top of the manifold. This side connection is objectionable however, because of the danger of the adjusting means coming in contact with the dirt tray when the latter is withdrawn from the stove and thus disturbing 35 the fine adjustment of the needle valve. Furthermore it is extremely difficult to reach the adjusting means when so positioned. It will also be seen that a pilot lighter which can at will be connected either to a front or centrally disposed manifold has many advantages.

40 According to the present invention it is possible to overcome the foregoing objections and attain the desideratum referred to by providing the lighter body with means whereby the latter can be adapted for connection to variously arranged manifolds.

Having thus described my invention:

What I claim is:

1. A valve of the character described comprising a housing having a discharge opening therein, a gas supply below said discharge opening, a needle valve longitudinally movable in said housing and controlling said discharge opening, said valve having a beveled end and provided with a 50 lateral lug at one end of the bevelled portion, and an operating member extending transversely into the housing and engaging the beveled end 55

and said lug preventing the operating means from being withdrawn beyond the side of said bevelled end.

2. A valve of the character described comprising a housing having a discharge opening at one end, a gas supply adjacent the opposite end of the housing, a needle valve longitudinally movable in said housing and controlling said discharge opening, a spring normally holding the valve unseated, said valve having a beveled end 10 and provided with a lateral lug at one end of the bevelled portion and an operating member extending transversely into the housing and engaging the beveled end of the valve, and said lug preventing the operating means from being 15 withdrawn beyond the side of said bevelled end.

3. A valve of the character described comprising an elongated housing having a discharge opening at one end, a gas supply adjacent the opposite end of the housing, a needle valve longitudinally movable in said housing and controlling said discharge opening, said valve having an enlarged end, a spring surrounding the valve between the enlarged end and the housing for normally holding the valve open, the end of the 25 enlarged portion of the valve being beveled and said beveled end provided at one end with a lateral lug, and an operating member extending transversely into the housing and engaging the beveled end of the enlarged portion of the valve, 30 and said lug preventing the operating means from being withdrawn beyond the side of said bevelled end.

4. In a valve of the character described comprising an elongated housing having a discharge 35 opening at one end, said housing having two threaded openings therein, arranged at right angles, a plug closing one of said threaded openings and a tubular member adapted to be connected to a gas supply in the other opening and so 40 arranged that said tubular member and plug can be transposed, a needle valve longitudinally movable in said housing and controlling said discharge opening, said valve having an enlarged end, a spring surrounding the valve between the 45 enlarged end and the housing for normally holding the valve open, the end of the enlarged portion of the valve being beveled and said beveled portion provided at one end with a lateral lug, and an operating member extending transversely 50 into the housing and engaging the beveled end of the enlarged portion of the valve, and said lug preventing the operating means from being withdrawn beyond the side of said bevelled end.

55 DANIEL J. SCHOENBERGER.
